COMBINATION SCHOOL DESK AND CHAIR

James E. McCall, Cavite, P. I.

Application June 3, 1935, Serial No. 24,734

3 Claims. Cl. 155—124)

The invention relates to schoolroom furniture and more especially to an adjustable combination school desk and chair.

The primary object of the invention is the provision of a unit of this character, wherein the same is made from an iron frame, with a steel base and a galvanized book box, these being practically indestructible, and when necessary these parts can be repaired at a minimum expense, the unit being light and susceptible of being maintained sanitary and in a hygienic condition.

Another object of the invention is the provision of a unit of this character, wherein both the desk and chair have a maximum range of adjustment, so that the unit is adaptable for use by children of varying sizes and is portable and readily and quickly knocked down for transportation, as well as being capable of erection with dispatch and without the necessity of skilled labor.

A further object of the invention is the provision of a unit of this character, wherein the same is of a construction as to allow the placing thereof within a classroom of a school to assure the most favorable light conditions without extravagant use of space, the unit being easily assembled and adjusted by one teacher aided by a pupil, there being but a single wrench required for the adjustment of the unit, and such unit meets all requirements for hygienic seating.

A still further object of the invention is the provision of a unit of this character, wherein the seat proper is ventilated to add to comfort when occupied, the unit being in its entirety of novel construction.

A still further object of the invention is the provision of a unit of this character which is comparatively simple in construction, thoroughly reliable and efficient in its purposes, strong, durable, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a side elevation of a unit constructed in accordance with the invention.

Figure 2 is a front elevation thereof.

Figure 3 is a rear elevation.

Figure 4 is a fragmentary vertical transverse sectional view taken on the line 4—4 of Figure 1 showing in detail the manner of adjustment.

Figure 5 is a fragmentary vertical transverse

sectional view through the desk of the unit, showing the range of adjustment thereof.

Figure 6 is a side elevation of those parts shown in Figure 5.

Similar reference characters indicate corresponding parts throughout the several views in the drawings.

Referring to the drawings in detail, the unit comprises a desk, designated generally at A, and a seat or chair designated generally at B, respectively. The unit includes a pair of spaced parallel base rails 10, each in the form of L irons and adapted to rest upon a foundation or flooring in the setting up of the unit and from which rise the desk A and seat or chair B, these being spaced 15 the desired distance from each other as required.

The desk A comprises a pair of end uprights in the form of iron frames 11 providing in their upper portions guideways 12 accommodating adjustable end brackets 13, these being slidably fitted in said uprights and carrying the desk top 14. At the underside of the desk top 14 is a pair of strips 15 which carry bolts 16 adapted for the adjustment of the top with relation to the top-piece 17 of each bracket 13. Confined in each bracket is a vertically slotted filler block 18, preferably of wood, the slot 19 of which is located centrally of the said block and receives a bolt 21 carried by a cross piece 22 of each upright 11. Thus it will be seen that the desk is susceptible of vertical adjustment and the top 14 thereof has the proper directional inclination to meet the requirements of the user of the desk for writing purposes.

Suspended from the underside of the top 14 of the desk A is a book box 23, it being made from sheet metal and conventionally constructed for accommodating books or other accessories usable by pupils in a classroom.

Connected with the uprights 11 at the front 40 side of the desk are cross braces 24, these being preferably bolted, as at 25, so that the desk A may be knocked down or set up in a convenient manner and when knocked down can be transported by occupying minimum space. Supplementing the cross pieces 22 of the uprights 11 are the cross pieces 26, these being near the upper ends of said uprights and at the outer sides thereof, while the cross pieces 22 are at the inner sides of said uprights and the brackets 13 slide between 45 said cross pieces.

The seat or chair B of the unit includes the side frames 27, each being fitted with a filler piece 28, preferably made from wood, and carried by said side frames 27 is a back rest 29, it having 50 55

near opposite ends the spaced cleats 30 accommodating bolts 31 which adjustably engage the side frames 27. This back rest 29 is formed to fit the curvature of the back in the dorsal lumbar region and is susceptible of being moved upwardly and downwardly and at the required pitch for health and comfort to an occupant of the chair or seat B, the adjustment being had through the medium of the bolts 31, as should 10 be obvious.

Carried by the side frames 27 is a seat proper or seat section 32, it including the spaced slats 33 for ventilating purposes, and at the underside of this section 32, near opposite ends, are the 15 pairs of spaced cleats 34, these having slots 35 receiving bolts 36 which are selectively received in holes or openings 37 spaced from each other and disposed in diagonal rows in the filler pieces 28. Thus it will be seen that the seat section 32 20 can be adjusted in a horizontal plane by manipulation of the bolts 36 and also in a vertical direction on selectively fitting the bolts 36 in the holes or openings 37 in the filler pieces 28 as carried by the side frames 27. The uprights 11 and the frames 27 have unity with each other through connecting strips 38, these being riveted to the base rails 10, while the said uprights and side frames 27 at meeting points with the said base rails 10 are welded or otherwise united with 30 each other, the uprights 11 being strengthened or reinforced by the diagonal braces 39 within the same. The seat section 32 at an intermediate point thereof carries a brace 40 secured between the seat and the diagonal braces. 35 It should be obvious that the desk A is susceptible of vertical adjustment to have the same disposed with its top 14 at the proper height for meeting the requirements of a pupil in using such desk. Also, the seat or chair B is susceptible of 40 adjustment so as to have the seat section 32 come close to or away from the desk A and also for permitting the raising and lowering of said seat section for meeting the requirements of the occupant thereof. 45 By removal of the bolts the parts of both the desk A and seat or chair B can be disassembled with dispatch so that transportation of the unit can be had in knocked-down form and to minimize occupancy of space during transportation. 50 The unit in its construction assures proper venti-

lation and also renders the same sanitary with hygienic conditions prevailing.

As has been stated, the desk top 14 can be moved forwardly or backwardly on manipulation of the bolts 16 connecting the same to the top 5 pieces 17 of the brackets 13. Each strip 15 in the side thereof next to the desk top 14 is provided with a channel or groove 41 communicating with elongated slots 42 receiving the bolts 16 and in this groove 41 is accommodated an iron clamp 10 plate 43.

What is claimed is:

1. As an article of furniture, a pair of uprights providing at their upper ends vertical guideways, adjustable end brackets fitting said guideways, 15 a desk top on said end brackets, means connecting the end brackets with the desk top for holding the latter in forward and rearward adjustment, a book box depending from the top between the uprights, and means for holding the end brackets 20 in vertical adjustment in the uprights.

2. As an article of furniture, a pair of uprights providing at their upper ends vertical guideways, adjustable end brackets fitting said guideways, a desk top on said end brackets, 25 means connecting the end brackets with the desk top for holding the latter in forward and rearward adjustment, a book box depending from the top between the uprights, means for holding the end brackets in vertical adjustment in the 30 uprights, cross pieces on the uprights, and vertically slotted filler blocks fitting the end pieces and having adjustable connection by the last-mentioned means with said cross pieces.

3. As an article of furniture, a pair of uprights providing at their upper ends vertical guideways, adjustable end brackets fitting said guideways, a desk top on said end brackets, means connecting the end brackets with the desk top for holding the latter in forward and rearward 40 adjustment, a book box depending from the top between the uprights, means for holding the end brackets in vertical adjustment in the uprights, cross pieces on the uprights, vertically slotted filler blocks fitting the end pieces and 45 having adjustable connection by the last-mentioned means with said cross pieces; and a chair connected with said uprights and having an adjustable seat.
